FIG. 3

INVENTOR

PAUL MILLER

BY *Thomas J. Ryan* ATTORNEY

UNITED STATES PATENT OFFICE

150,437

DESIGN FOR A COMBINED HAMMER AND
POUNDING TOY

Paul Miller, Muncie, Ind.

Application February 4, 1947, Serial No. 136,664

Term of patent 14 years

(Cl. D34—15)

To all whom it may concern:

Be it known that I, Paul Miller, a citizen of the United States, residing at Muncie, in the county of Delaware and State of Indiana, have invented a new, original, and ornamental Design for a Combined Hammer and Pounding Toy, of which the following is a specification, reference being had to the accompanying drawing, forming a part thereof.

Figure 1 is a side view; Figure 2 is a front view, and Figure 3 is a top plan view of a combined hammer and pounding toy, showing my new design.

I claim:

The ornamental design for a combined hammer and pounding toy, as shown.

PAUL MILLER.
